UNITED STATES PATENT OFFICE.

ALFRED ERNEST HUDD, OF WALLASEY, ENGLAND, ASSIGNOR, BY MESNE ASSIGNMENTS, TO AUTOMATIC ELECTRIC INC., OF CHICAGO, ILLINOIS.

ELECTROMAGNETIC RELAY DEVICE.

Application filed October 31, 1925, Serial No. 65,981, and in Great Britain August 22, 1925.

The present invention concerns improvements in or relating to electromagnetic mechanisms for operating relay contacts or the like. The object of the present invention is to provide a polarized electromagnetic mechanism which is adapted to take up in a reliable and positive manner any one of three operating positions according as to whether it is energized positively or negatively or not 10 energized at all. Moreover the arrangements are such that, if for any reason the polarizing field should fail, the electromagnetic mechanism will remain in the neutral position.

The positiveness of a polarized relay in its deenergized position used for controlling such vital circuits as are demanded in railway signalling is a very desirable feature. To this end and according to the present invention the polarizing field is arranged to 20 operate in such manner as to assist the normal restoring forces in maintaining the relay armature in its normal position on the failure of energizing current.

The operating member of the relay is 25 adapted to take up two different positions according to the direction of the exciting current while its armature is adapted to operate always in the same direction irrespective of the direction of the exciting current, magnetic attraction between the operating member and the armature ensuring the movement of the former when the latter is attracted.

In order that the invention may be clearly understood and readily carried into effect, a 35 polarized electromagnetic mechanism or relay in accordance with the invention will now be more fully described with reference to the annexed drawings which show by way of example the invention applied to two types 40 of relays particularly suitable for use in railway signalling systems.

In the drawings comprising Figs. 1, 2, 3, 4, 5, and 6, Figs. 1, 2 and 3 show end elevations of a three position polarized relay in its normal and two energized positions respectively, while Fig. 4 shows a side elevation of the same relay. Fig. 5 shows a side elevation of a two position polarized relay and Fig. 6 an end elevation of the same relay.

The three position polarized relay has a de-energized position shown in Fig. 1, one position when energized with say positive current shown in Fig. 2 and one position when energized with negative current shown 55 in Fig. 3. The two position relay shown in

Figs. 5 and 6 is polarized in such manner that, say positive current or no current will assist the normal restoring forces of the relay to maintain it in an inoperative position and that negative current only will operate the 6 relay to close its contacts.

Referring to Figs. 1, 2, 3, and 4 it will be seen that the relay comprises a fixed solenoid or helix 3, an armature 1, a swinging contact carrier 5 of non-magnetic material, and a 65 permanent magnet 8. The armature consists of a bar extending through the rectangular opening in the solenoid 3 and is pivoted on a pair of non-magnetic brackets 2, (one shown in Fig. 4) secured to a downwardly extending 70 portion 9 of the pole piece 10. The free end of this armature is formed into an arch comprising extensions 4 and 4^a, as shown in Figs. 1-3. Fig. 4 also shows the extension 4 and indicates, by use of interrupted lines, that 75 part of the armature which extends through the solenoid or helix.

The swinging contact carrier 5 is of non-magnetic material and is pivoted on bearings 6 and 7. The permanent magnet 8 comprising an ordinary steel bar, is traversely fixed by clips 12 and 13 to the carrier 5, so that the north and south poles of the permanent magnet are positioned immediately below the extensions 4 and 4^a. When there is no current flowing through the solenoid the armature normally drops by gravity until the extensions 4 and 4^a encounter the north and south poles of the permanent magnet, and the extensions therefore normally hold the carrier in 85 its central position as shown in Fig. 1. While the relay is in this position the extensions 4 and 4^a serve as a keeper for the permanent magnet. The foregoing is the "no current" 90 condition of the relay.

A return magnetic path for the armature 1 is provided by means of the limb 9 which terminates in a pole piece 10, which completes the magnetic circuit through the short-air-gap 11 to the top-side of the armature 1.

When say a positive current is passed through the winding of the solenoid 3 the armature 1 is pulled up toward the pole piece 10, in so doing however, it will drag one end of the permanent magnet 8 with it, and thus close 100 the contact making fingers 14 on one side of the carrier 5. The particular end or pole of the permanent magnet 8 which is lifted is determined by the polarity produced in the pole extensions 4 and 4^a.

When the current flow through the winding of the solenoid is in one direction the extensions 4 and 4^a will be of north polarity. Under these circumstances the south pole of the permanent magnet will remain attracted to extension 4^a, as illustrated in Fig. 2, and this end of the permanent magnet will follow the upward movement of the extension 4^a. This upward movement of the south pole of the permanent magnet is assisted by the repelling action between the extension 4 and the north pole of the permanent magnet.

When the current flow is in the reversed direction, the extensions 4 and 4^a become of south polarity, and therefore in this case the north pole of the permanent magnet will be lifted by the extension 4 of armature 1.

It will be seen that in this manner the actual work done to effect the closing of the contacts 14 on either side of the relay is performed by the lift of the armature 1 toward the pole piece 10. The selection or determination of which series of contacts 14 requiring to be closed is determined entirely by the polarity of the permanent magnet 8 in its relation to the polarity of the pole extensions 4 and 4^a.

Referring now to the two position polarized relay shown in Figs. 5 and 6, it will be seen that in this structure no rocking carrier is required as only one series of contacts are used to be operated when the relay is deenergized.

This relay comprises a mounting panel to which are secured two non-magnetic supports 30 and 30'. These supports are drilled and serve as bearings for the reduced portions 22 and 23 of core 21 of an electromagnet comprising core 21 and winding 20, as shown in Figs. 5 and 6.

Just outside each end of the winding 20 the core is slightly reduced and at these points extends through pole pieces 24 and 24^a in fixed relation thereto. These pole pieces comprise soft iron bars the ends of which are connected together with non-magnetic contact carriers 32 and 32', respectively.

The rotary movement of the pole piece and carrier unit thus constructed is limited in one direction by a permanent magnet in the form of a bar 26 which extends across the bottom end of supports 30 and 30'. Movement in the opposite direction is limited by an armature comprising a soft iron bar 27 fixed to the supports 30 and 30' and lying against the mounting panel. With this construction, as in the three position relay, the movable magnetic elements, in this case bars 24 and 24^a, are normally attracted and held in engagement with the north and south poles of the permanent magnet, leaving air-gaps 28 and 29 between the bars 24^a and 24 and the fixed armature 27.

The operation of the relay is as follows:

If direct current is passed through the winding on the iron core 21 in such a direction as to produce a north pole at 24 and a south

pole at 24^a, with the permanent magnet 26 having its north pole adjacent to the pole piece 24, and its south pole adjacent to the pole piece 24^a as shown in Fig. 5, repulsion of the poles 24 and 24^a from the poles of the permanent magnet will take place and the whole coil winding with its core 21 will rotate on the bearings 22 and 23. This rotation will be assisted thereto by the pull of its pole-pieces 24 and 24^a to the fixed armature 27, thus operating the contact fingers 31 as desired.

If, however, a reverse current is passed through the winding, the poles 24 and 24^a will become of unlike polarity to the poles of the permanent magnet 26. The mutual attraction existing under this state of affairs prevents any movement of the iron core 21 taking place. The effect of no current or one of incorrect direction is therefore the same and the relay contacts are thus held positively in their normal position in either case.

What I claim and desire to protect by Letters Patent is:

1. In an electromagnetic mechanism of the polarized type, an operating member adapted to take up two different positions and an armature adapted to operate always in the same direction irrespective of the direction of exciting current to bring about the movement of the operating member to either of its positions.

2. In an electromagnetic device, a permanent magnet, an electro-magnet, and an armature of said electromagnet influenced by the polarizing field set up by said permanent magnet when said electromagnet is deenergized and effective when said electromagnet is energized to influence said permanent magnet.

3. In an electromagnetic device, a permanent magnet, an electromagnet, an armature for said electromagnet normally engaging both poles of said permanent magnet, and a magnetic circuit produced by the energization of said electromagnet effective to cause said armature to break away from one or the other pole of said permanent magnet dependent on the direction of current flow through the said electromagnet.

4. In an electromagnetic device, an operating winding in the form of a solenoid, a pole piece for said magnet, and an armature pivoted to one end of said pole piece and extending through said coil into close proximity to the other end of said pole piece.

5. In an electromagnetic device an operating winding in the form of a solenoid, a pole piece for said magnet, an armature pivoted to one end of said pole piece and extending through said coil into close proximity to the other end of said pole piece and a permanent magnet operated by said armature when the said winding is energized.

6. In an electromagnetic device, an operat-

- ing winding in the form of a solenoid, a pole piece for said magnet, an armature pivoted to one end of said pole piece and extending through said winding into close proximity to the other end of said pole piece, and a permanent magnet operated in one manner by said armature when the said winding is energized by current flow through it in one direction and in a different manner when the current flow is in the opposite direction.
7. In an electromagnetic device, an electromagnet, an armature for said electromagnet operated thereby in the same manner irrespective of the direction of current flow through said electromagnet, contacts controlled by said armature responsive to its actuation by current flow in one direction and other contacts controlled by a like movement of said armature responsive to current flow in the opposite direction.
8. In an electromagnetic device, an electromagnet, an armature therefor operated in the same manner irrespective of the direction of current flow through said electromagnet, and contact springs normally held in one position by the armature when the electro-magnet is deenergized and means actuated by said armature to move said contact springs in one of two alternative positions when the electro-magnet is energized depending on the direction of current flow through said electromagnet.
9. In an electromagnetic mechanism of the polarized type, an armature, an operating member carrying a permanent magnet acted upon by said armature to maintain said operating member in definite relation thereto during the absence of current flow, said permanent magnet being positioned adjacent to one pole of said armature so that due to its magnetic characteristics it assists the normal restoring forces in maintaining the armature in its normal position.
10. In a three position electromagnetic device, a movable member, an electromagnet and associated armature for moving said member in response to current flow through the electromagnet and a permanent magnet in fixed relation to said member normally cooperating with said armature to hold said member in a neutral position while no current is flowing through said electromagnet.
11. In an electromagnetic device, a pivoted member having a permanent magnet secured thereto, an electromagnet having an armature normally bridging the gap between the poles of said magnet, the relative position of the pivot of said member with respect to that of the armature being such that when no current is flowing through the electromagnet the armature and magnet will force the member into a neutral position.
12. In an electromagnetic device, an electromagnet, an armature, a pivotally secured permanent magnet, for the electromagnet normally bridging the magnetic gap between the poles of said permanent magnet, the said armature being neutral while no current flows through said electromagnet and therefore being normally attracted by both poles of the permanent magnet, but becoming a north or south pole while current flows, the direction of current flow being effective to cause one pole of said permanent magnet to oppose and the other to strengthen the attraction between the said armature and magnet so that one pole of the permanent magnet follows the movement of the armature while the other assists this follow up action by its opposing action.
13. In an electromagnetic mechanism, an electromagnet, an armature for said electromagnet, a permanent magnet normally having its poles in contact with said armature, and contact members associated with said permanent magnet influenced by the armature of said electromagnet in a manner dependent on the direction of current flow therethrough.
14. In an electromagnetic device, a contact carrier pivoted at its central point, a permanent magnet carried by said contact carrier and lying parallel thereto, an electromagnet associated with said contact carrier, an armature for said electromagnet pivoted in a plane at right angles to the pivot of said carrier and having extensions normally holding said carrier in a central position, said armature being effective when the electromagnet is energized to disconnect and repel one of the permanent magnet poles and to strengthen and carry with it the other pole of said permanent magnet.
15. In an electromagnetic mechanism of the polarized type, a neutral armature, an electromagnet effective to actuate said armature, and a contact carrier operated by said armature in a manner dependent on the direction of current flow through said electromagnet.
16. In an electromagnetic mechanism, a permanent magnet, an electromagnet, and an armature for said electromagnet normally acting as a keeper for said permanent magnet.
17. In an electromagnetic mechanism, an armature therefore, an electromagnet for lifting said armature, and a permanent magnet for assisting the restoration of said armature when the influence of said electromagnet ceases.
18. In an electromagnetic mechanism, a contact carrying element, an armature, an electromagnet effective when energized to attract said armature into the same definite relation to said electromagnet irrespective of the direction of current flow through said electromagnet, and means associated with said carrier and armature for causing said armature to move said carrier in a direction dependent on the direction of current flow through said electromagnet.
19. In a polarized relay, a permanent magnet pivotally secured, an electromagnet

- equipped with an armature having one of its poles normally in engagement with both of the poles of said permanent magnet, and an exciting winding for actuating said armature to cause the same to in turn attract and move with it one pole of the permanent magnet and repel from it the other pole, the pole attracted being directly dependent on the polarity of the said armature.
- 10 20. In an electromagnetic mechanism, an exciting winding, a neutral armature, and a movable permanent magnet actuated by said armature in a manner dependent on the direction of current flow through said winding.
- 15 21. In an electromagnetic device, a permanent magnet, an electromagnet, an armature for said electromagnet permanently magnetically attracted and held in contact with said permanent magnet, and electro mechanical means effective upon energization of said electromagnet to move said armature in a definite direction irrespective of the direction of current flow and to bring about a movement of said permanent magnet in a direction depending on the direction of current flow. 20
22. In an electromagnetic device, an electromagnet, a three position armature, and a two position armature for moving said three position armature to any of its positions. 25

In testimony whereof I affix my signature.

ALFRED ERNEST HUDD.
